CLAIM

The ornamental design for a light fixture, as shown and described.

DESCRIPTION

FIG. 1 is a bottom isometric view of a light fixture.

FIG. 2 is another bottom isometric view of the light fixture of FIG. 1.

FIG. 3 is a bottom view of the light fixture of FIG. 1; and, FIG. 4 is a cross section view of the light fixture of FIG. 1. The dash-dot-dash broken lines in the drawings illustrate a boundary of the claimed design, and form no part of the claimed design. The dashed lines illustrate unclaimed portions of the light fixture, and form no part of the claimed design.
